UNITED STATES PATENT OFFICE.

WILLIAM H. BURT, OF CHICAGO, ILLINOIS.

DESIGN FOR A BED OR MATTRESS FOR HORSES.

SPECIFICATION forming part of Design No. 25,626, dated June 9, 1896.

Application filed September 16, 1895. Serial No. 562,719. Term of patent 14 years.

To all whom it may concern:

Be it known that I, WILLIAM H. BURT, a citizen of the United States, residing at Chicago, county of Cook, and State of Illinois, have invented and produced a new, useful, and original Shape or Design for a Bed or Mattress for Horses and other Animals, of which the following, in connection with the accompanying drawings, is a full, clear, and exact specification.

In the said drawings, Figure 1 is a plan view of the bed or mattress embodying my design and shown in its open or flat condition; and Fig. 2 is a rear view thereof, showing it in the position in which it is used, on an enlarged scale.

The leading features of my design consist of the two portions A B, of oblong shape and extending parallel with each other and longitudinally of the bed or mattress, the web C, of less length than the portions A B and apparently joining the portions A B together along their upper inner edges and at a slight distance apart and being depressed or countersunk below the surface of the portions A B, the portions A B extending upwardly or outwardly from the upper side of the web C, so that such portions A B will appear like raised pads when secured on the animal and viewed as in Fig. 2.

The portion C is in the form of a thin web, which apparently joins the portions A B together, and which extends throughout the greater part of their length, but falls a little short of the ends of the portions A B at each end and a little more at one end than at the other.

The rear ends of the portions A B are connected together by the curved strip D, while the forward or opposite ends of such portions A B are each provided with a pair of strips E, and extending substantially at right angles from the sides of each of the portions A B and from their lower inner edges, as shown in Fig. 2, is a pair of strips F G, respectively.

Having thus described my invention, what I claim as new, and desire to secure by Letters Patent, is—

1. A design for a bed or mattress for horses and other animals, substantially as shown and described.

2. A design for a bed or mattress for horses and other animals consisting of the two portions A, B of oblong shape and extending parallel with each other and longitudinally of the bed; the web C of less length than the portions A, B and apparently joining the portions A, B together along their upper inner edges and at a slight distance apart and being depressed or countersunk below the surface of the portions A, B; the portions A, B, extending upwardly or outwardly from the upper sides of the web C so that such portions A B will appear like raised pads when secured on the animal and viewed as in Fig. 2; the curved strip D extending from the end of one of said portions A B to the end of the other; and the strips F, G extending from the sides of the portions A, B, substantially as herein shown and described.

WILLIAM H. BURT.
